WATCH BRACELET

Emile Bollier, Route de Boujean 46,
Bienne, Switzerland

Filed Dec. 14, 1966, Ser. No. 65,031

Term of patent 14 years

(Cl. D45—4)

I claim:

The ornamental design for a watch bracelet, as shown.
